UNITED STATES PATENT OFFICE.

JETTIE P. GLENN, OF FORT PIERCE, FLORIDA.

HAT HOLDER.

1,410,468.

Specification of Letters Patent. Patented Mar. 21, 1922.

Application filed August 9, 1921. Serial No. 490,920.

To all whom it may concern:

Be it known that I, JETTIE P. GLENN, a citizen of the United States, and a resident of Fort Pierce, in the county of St. Lucie 5 and State of Florida, have invented a new and Improved Hat Holder, of which the following is a full, clear, and exact description.

This invention relates to improvements 10 in hat holders, an object of the invention being to provide a device of this character adapted to be secured to the under face of an automobile top and to conveniently engage the brim of a hat to support the hat 15 in inverted position.

A further object is to provide a device of the character stated, which will be neat and attractive in appearance, which will be 20 take up very little room, which will be strong and durable in use and comparatively inexpensive to manufacture.

With these and other objects in view, the invention consists in certain novel features of construction and combinations and arrangements of parts to be more fully hereinafter described and pointed out in the 25 claims.

In the accompanying drawings;

Figure 1 is a plan view of my improved 30 holder, the holder being illustrated in closed position;

Figure 2 is a view similar to Figure 1 illustrating the holder in open position to receive a hat;

Figure 3 is an enlarged view in section 35 on the line 3—3 of Figure 1, illustrating the manner of use of the holder; and

Figure 4 is an enlarged view in section on the line 4—4 of Figure 1.

Referring in detail to the drawings, 1 represents the top of an automobile, to the under face of which, my improved hat 40 holder is attached.

The hat holder comprises a substantially 45 oval sheet of material 2, having its edges secured to the top 1 in any approved manner. Upon the face of this oval sheet 2, I secure a split oval ring 3 of any appropriate kind of cloth. The ring is preferably 50 of the same kind of cloth as the top of the car and the outer edge of the ring 3, throughout substantially one half of its periphery is secured to the outer edge of the sheet 2 by tape 4.

The edges of the sheet 2 and ring 3 are 55 also taped, as indicated at 5, to add to the

attractive appearance of the holder. The other half of the periphery of the member 3 carries snap fastener socket members 6 engageable with snap fastener stub members 60 7 on the sheet 2. The member 3 is radially split, as indicated at 8, and the adjacent ends 9 of the member 3 are adapted to overlap and be removably joined together by snap fastener members such as 10. 65

The sheet 2 and the member 3 are both lined with any suitable material, indicated by the reference numeral 11.

It is to be understood that when a hat is to be inserted in the holder, the adjacent 70 edges 9 of the member 3 are uncoupled, the snap fastener members 6 and 7 are disengaged and the ends of the member 3 are swung back to permit the introduction of a hat such as 12 between the sheet 2 and the 75 member 3. The ends of the member 3 are then returned to and secured in the position illustrated in Figure 1, so that the brim 13 of the hat 12 is embraced and supported by the annular member 3, as seen in Figure 80 4. The crown of the hat depends through the opening 14 in the ring shaped member 3.

For convenience of attachment, I have illustrated the snap fastener members 7 as carried by tabs 16, which are sewed to the 85 lining of the sheet 2, but obviously the details of construction might be considerably varied without departing from my invention and hence I do not wish to limit myself to the precise details set forth, but shall 90 consider myself at liberty to make such slight changes and alterations as fairly fall within the spirit and scope of the appended claims.

I claim:

1. A device of the character described including a flat sheet of material adapted to be secured to a support, a split ring of flexible material having one portion of its outer edge permanently secured to the sheet and the remainder of its outer edge removably secured thereto. 95 100

2. A device of the character described including a flat sheet of material adapted to be secured to a support, a split ring of flexible material having one portion of its outer edge permanently secured to the sheet and the remainder of its outer edge removably secured thereto, the ends of said split ring overlapping and devices removably connecting said ends. 105 110

3. The combination with an automobile top, of a flat sheet of material secured to

the under face of the top, a split ring of flexible material having a portion of its outer edge secured to the sheet, tabs secured to the sheet, securing devices carried by the tabs, securing devices carried by the other portion of the outer edge of the split ring and interlocking with said first-mentioned

securing device whereby the brim of a hat may be confined between the sheet and ring.

4. A hat holder comprising a sheet of 10 flexible material, and a split ring of flexible material having its outer edges secured to the sheet.

JETTIE P. GLENN.
